[57] CLAIM

The ornamental design for sunglasses, as shown and described.

DESCRIPTION

FIG. 1 is a perspective view of the sunglasses embodying my new design in place on an individual;

FIG. 2 is a perspective view of the sunglasses embodying my new design as configured during use;

FIG. 3 is a side view of the sunglasses embodying my new design as configured during use;

FIG. 4 is a second side view of the sunglasses embodying my new design as configured during use;

FIG. 5 is a top view of the sunglasses embodying my new design as configured during use; and,

FIG. 6 is a bottom view of the sunglasses embodying my new design as configured during use.

The broken line showing of the cord and head are for illustrative purposes only and form no part of claimed design.
